LENS EDGING MACHINE

Eli Maynard Long, Geneva, N. Y., assignor to
Shuron Optical Company, Inc., Geneva, N. Y.,
a corporation of New York

Original application October 2, 1937, Serial No.
167,008. Divided and this application August
15, 1938, Serial No. 224,870

4 Claims. (Cl. 125—11)

This invention relates to improvements in a lens edging machine in which a lens holding means operates in conjunction with a rotating abrasive stone or wheel and is a division of my copending application Serial No. 167,008, filed October 2, 1937, now Patent No. 2,175,719, granted October 10, 1939.

The object of this invention is to provide a lens edging machine with an improved truing device for maintaining the peripheral or grinding surface of the abrasive wheel in the most advantageous form and condition for precision grinding.

In carrying out the object of this invention, I have provided a truing hone which is substantially rectangular in form. This hone is mounted so that an end thereof may traverse the peripheral grinding surface of the wheel and be maintained by the action of the wheel thereon substantially flat and normal to the longitudinal center line of the hone to thereby most efficaciously clean, sharpen and true the grinding surface by always maintaining a line contact between the hone and said surface.

Other objects and advantages pertaining to the construction of the device and to the form and relation of the parts thereof will more readily appear from the following description taken in conjunction with the accompanying drawing, in which:

Figure 1 is a fragmentary top plan view of a lens edging machine illustrating a truing device for the abrasive wheel which embodies the various features of this invention.

Figure 2 is a detail vertical sectional view taken on line 2—2, Figure 1.

Figure 3 is a detail transverse sectional view taken substantially on line 3—3, Figure 2.

As illustrated in the drawing, the machine comprises a supporting base or frame 1 composed of two sections, a lower section 2 and an upper section 3 which may be fixedly secured together in any suitable manner, as by screws 4. The abrasive wheel 5 may be secured in any suitable manner to a shaft (not shown) rotatably carried by the frame 1 so as to rotate about a horizontal axis extending transversely of said frame. In other words, the wheel 5 may be carried, as shown in the above mentioned copending application, in a cradle received within the chamber 2' of the lower base section 2, the rear end of the cradle being rotatably connected with the base and the forward end thereof supported by an adjusting screw or bolt 14 having screw-

threaded engagement with the forward portion of the cradle and which is carried by an offset portion 3' of the upper base section 3, as indicated in Figure 2 of the drawing. The bolt 14 may be utilized for adjusting the forward end of the frame or cradle and thereby elevate the wheel 5 as the same wears away in use for maintaining the peripheral surface of the wheel in cooperative relation with a lens holder 16 which is mounted on the upper section 3 of the main supporting base or frame 1 in a plane above the wheel 5.

In Figure 1, I have indicated a lens holder 16 associated with the abrasive wheel 5 and which, in this instance, comprises opposed coaxial clamping heads 17 and 17' mounted end to end upon coaxial rotary shafts or spindles 18 and 18' which in turn are journaled in suitable bearings (not shown) provided in the outer or free portion of a vertical swinging frame or carriage 20 supported in any suitable manner by the frame 1.

In other words, the swinging frame or carriage 20 may be pivotally connected in the manner shown in my copending application Serial No. 167,008 to the rear portion of the upper section 3 of the base 1 to swing about an axis extending substantially normal to the axis of rotation of the wheel 5 and spindles 18 and 18'. The adjacent ends of the lens clamping heads 17 and 17' may be provided with the usual pads 25 composed of rubber, leather or the like for frictionally engaging the opposite surfaces of the lens to cause the latter to rotate with the heads and also to reduce the liability of breakage or marring the lenses when clamping them between the heads.

In order that the heads 17 and 17' may be moved into and out of clamping engagement with a lens, one of said heads, as 17', and the shaft 18' connected therewith may be mounted for axial movement in its respective bearing member and any suitable means may be provided for manually moving said head and shaft with respect to the other head and shaft.

It will be understood that any suitable means may be employed for producing relative movement of the lens holder and the wheel 5 to maintain the lens carried by the heads 17 and 17' in pressure engagement with said wheel. Furthermore, the path of movement of the heads 17 and 17' with respect to the wheel 5 to maintain the lens in proper relation with said head may be produced by any suitable means which

it is not believed necessary to further illustrate or describe inasmuch as these elements do not constitute a portion of the novel features of the invention covered by this application.

- 5 In order that the abrasive wheel 5 may be maintained in the most efficient grinding condition, I have provided a novel truing device which is operatively connected with the base 1 to be used as occasion may require. This truing 10 device, as shown more clearly in Figure 2, comprises a substantially rectangular hone or carbide stick 165 which is adjustably clamped by a plate 166 and screws 167 to the head 168 of a support 169. This support 169 includes a 15 cylindrical extension 170 connected with the head 168 and which extends outwardly therefrom through a sleeve 171 screw-threaded in a suitable aperture 172 formed in the front wall of the upper base section 3.
- 20 The inner end of the sleeve 171 engages a shoulder 173 provided on the support 169 at the junction of the portion 170 with the head 168. The extension 170 projects a short distance outwardly from the sleeve 171 and has a lever 174 25 secured thereto, whereby the holder 169 may be rotated about the axis of the extension 170. This handle 174 engages the outer end of the sleeve 171 and coacts with the shoulder 173 for preventing relative axial movement of the support 169 and 30 sleeve 171. The support 169 is adjusted axially toward and from the wheel 5 by the axial movement of the sleeve 171 as the same is screw-threaded into and out of the opening 172.
- In order that the sleeve 171 may thus be readily 35 turned to effect the axial adjustment thereof, I have provided the outer end portion of said sleeve with a hand wheel 175. The sleeve 171 is secured in the adjusted position by a screw 176 mounted in the base section 3. The position of the sleeve 40 171 in the base section 3 is such that the hone 165 will extend in substantially radial relation to the abrasive wheel 5 with the inner end of said hone normally arranged in parallel relation with the adjacent portion of the peripheral surface of the 45 abrasive wheel. The width of the hone 165, as shown in Figure 3, is substantially equal to the width of the wheel 5. The distance the hone 165 is arranged at one side of the axis of rotation of the head 168 preferably exceeds one-half the 50 width of the abrasive wheel so that the hone will swing back and forth across the face of the stone in an arc X—X having its center lying in the axis of the extension 170. It will, therefore, be seen that instead of the inner end of the 55 hone having a concave recess ground therein during the truing of the wheel 5, said end of the hone will be maintained substantially flat with the result that the hone will have a line contact with the peripheral surface of the wheel 5 during the 60 truing operation. The hone will, therefore, true the abrasive wheel surface much more rapidly and accurately than when the hone is operated in the conventional manner, that is, toward and from the surface of the abrasive wheel in a 65 straight line substantially normal to said surface,

whereby the inner end of the hone engages the surface of the wheel throughout substantially its entire area. The head 168 may, as shown, be provided with a recess 168' extending inwardly from the end thereof adjacent the wheel 5 for 5 the reception of a sponge 178 adapted to normally bear against the peripheral surface of the wheel for preventing water and dust collecting on the hone 165.

10 Although I have shown and particularly described the preferred embodiment of my invention, I do not wish to be limited to the exact construction shown, as various changes, both in the form and relation of the parts thereof, may 15 readily be made without departing from the spirit of the invention as set forth in the appended claims.

I claim:

1. In a grinding machine of the class described, 20 an abrasive wheel, means including a base rotatably supporting said wheel, a truing hone for the abrasive wheel, and supporting means for the hone rotatably connected with the base for swinging said hone back and forth across the peripheral surface of the abrasive wheel in a plane substantially parallel with the axis of the wheel and about an axis arranged at one side of the hone and in a line extending substantially normal to a plane extending through the axis of rotation 30 of the abrasive wheel.

2. A grinding machine as in claim 1 wherein 35 said latter supporting means includes an adjustable element whereby the hone may be moved toward and from the abrasive wheel.

3. In combination, a rotary grinding wheel, a 40 substantially rectangular truing hone for said wheel, and supporting means for said hone including an operating element journaled to rotate about an axis arranged at one side of the longitudinal center of the hone and in a plane extending substantially normal to the axis of rotation 45 of the wheel, and means adjustably clamping the hone to said element at one side of the axis of rotation thereof with an end of said hone in position to operatively contact the peripheral surface of the wheel during rotation of the holding element, whereby said end of the hone will be ground into a curvature greater than that of the peripheral surface of the wheel during the truing 50 operation and thus maintain a line contact only between the hone and wheel.

4. In a lens grinding machine, the combination 55 with a rotary abrasive wheel having a substantially flat peripheral surface for operating on a lens, of a dressing device for said wheel comprising a truing hone having a substantially flat grinding surface, and rotatable supporting means for said hone, said supporting means including a spindle and means connecting the hone to said spindle so constructed and arranged that the 60 grinding surface of said hone will swing in a circular path through a plane substantially tangent to said peripheral surface of the wheel and about an axis substantially normal to said plane.

ELI MAYNARD LONG.
